UNITED STATES PATENT OFFICE

2,039,049

PRINTING DEVICE

Stanley Anthony, Boston, Mass., assignor to Far-
ington Manufacturing Company, Boston,
Mass., a corporation of Massachusetts

Application January 8, 1935, Serial No. 871

9 Claims. (Cl. 101—369)

In the art of printing devices of the type now generally used in department stores for printing names and addresses on sales slips and the like with small embossed plates carried by the customers as identification tokens, it is customary to provide a carrying case for each plate, such cases usually being formed of leather or other flexible material.

The object of the present invention is to provide a carrying case which prevents distortion of the plate while carried in a purse or pocket, which is also light and compact, which prevents access of the customer to the plate, which permits removal of the plate from the casing only by means of an unlocking device retained by the department store or other authorized agency, which affords ready removal of the plate by the store clerk or the like, and to provide an unlocking device which is simple and reliable in construction, which performs the unlocking operation in response to straight-line or rectilinear movement of the case into the device, and which also ejects the plate at least partially from the casing.

For the purpose of illustration a typical embodiment of the invention is shown in the accompanying drawing in which:

Fig. 1 is a side elevation of a printing or stamping machine having one of the aforesaid unlocking devices;

Fig. 2 is a section on line 2—2 of Fig. 1;

Fig. 3 is an end view, with parts broken away, of the printing plate holder;

Fig. 4 is a plan view of the printing side of the embossed printing plate;

Fig. 5 is an end view of the printing plate, viewed from the end which is inserted foremost into the aforesaid plate casing;

Fig. 6 is an end view of the plate and casing telescoped together;

Fig. 7 is a section on line 7—7 of Fig. 6;

Fig. 8 is a section on line 2—2 of Fig. 1, showing the parts in the position which they occupy after the plate casing has been inserted into the unlocking device and the plate has been partially ejected from the casing; and

Fig. 9 is a section on line 9—9 of Fig. 1.

The particular printing machine shown for the purpose of illustration comprises a base 1 having a bottom 2 adapted to rest on a table or the like and an upper portion 3 for supporting the sheet or sheets to be printed, the parts 2 and 3 being separated by a space 4 to receive a salesbook or the like with the uppermost sheet or sheets of the book resting on the platform 3. The upper side of the platform 3 is provided with a flat

central surface 5 to back up the central portion of the printing plate, the flat surface 5 being surrounded by a shallow depression 6 to receive the flanges around the edges of the printing plate. Pivotedly mounted on the base 1 is a pressure head 7 arranged to swing upwardly and to the right (Fig. 1) to receive the sheet to be printed between the platform 3 and the bottom of the head. A roller 8 is mounted in the head to roll an ink ribbon against the upper surface 10 of the sheet to be printed, the roller being actuated by arms 9 and a handle 10. The ink ribbon feeds transversely under the head between two ribbon rolls mounted in casings 11, one of which is shown in Fig. 1. The ribbon is fed step by step 15 from one roll to the other by means of a ratchet wheel 12 and a pawl 13, the pawl being pivoted on the head 7 so as to be actuated by engagement with the platform 3 each time the head is swung downwardly to the position shown in Fig. 1. A 20 machine of this kind is described and claimed in my copending application Serial No. 575,775, filed November 18, 1931.

The printing plate 14 shown in Figs. 4 and 5 is formed of sheet metal with printing letters embossed therein as shown in Fig. 4. Opposite edges of the plate are bent to form stiffening flanges 15, one of which has a notch 16 cooperating with a pin 17 in the printing machine (Fig. 2) so that only plates intended to be used in a particular 30 machine will fit into printing position in that machine. One end of the printing plate has a tab 18 for removing the plate from its casing, and the other end has a bent-down flange to provide shoulders for locking the printing plate in its 35 casing, the flange 19 having two cut-out portions 20 to receive the latches hereinafter described.

The printing plate casing shown in Figs. 3, 6, 7 and 8 comprises top and bottom plates 21 and 22, the lateral margins of the plates being bent at right angles into overlapping relationship and being permanently united by solder or other suitable means. As shown in Fig. 6 the plates 21 and 22 have no flanges on the end through which the printing plate is inserted and at the opposite end 40 the plates are provided with overlapping flanges having a central opening 23 and two side openings 24. The space defined by the plates 21 and 22 is preferably just large enough to receive the printing plate when inserted flatwise.

The mechanism for latching the printing plate in its casing comprises two plates 25 and 26 spaced slightly apart and interconnected along corresponding edges by integral bridges 27 separated by a central opening 28 and two lateral 55

openings 29. Latches 30 are pivotally mounted between the plates 25 and 26 by means of rivets 31, which also serve to interconnect the two plates, the latches extending out through the 5 openings 28 into position to engage the flange 19 of the printing plate when the plate is inserted into the casing 21—22. Each latch 30 has a shoulder 31 adapted to engage behind a lateral portion 32 of the flange 19 and, somewhat nearer 10 the forward end of the latch, another shoulder 33 adapted to engage behind the central portion of the flange 19 when the latch is swung toward the center of the casing beyond the unlatching position shown in Fig. 8. A spring 34 is provided 15 to urge each latch outwardly about its pivot. The outer ends of the latches are tapered so that when the plate is inserted into the casing the latches are automatically cammed toward the center until the flanges 32 pass the shoulders 31 where- 20 upon the latches snap into locking position. In order to unlock the plate the latches must be simultaneously swung inwardly to the position shown in Fig. 8 and if either latch is swung too far its inner shoulder 33 will engage behind the 25 central portion 19 of the plate flange, thereby rendering it difficult to remove the plate with any means other than an unlocking device de- 30 signed especially for this particular latching mechanism. The latching unit is held in position 35 in the plate casing by means of shoulders 50 formed by cutting away the ends of the flanges of the bottom plate 22 of the casing, the unit being restrained against endwise movement by the flanges of the top plate 21 and against movement away from the shoulders 50 by the overlapping end flanges of the two plates.

The unlocking device shown at 35 in Fig. 1 and in section in Figs. 2, 7, 8 and 9 comprises a socket shaped to receive the plate casing in snug 40 sliding relationship, the device comprising a bottom plate 36 having a downturned flange for attachment to the base 1 of the printing machine by means of a screw 37 and having side flanges 38 turned upwardly. The device also 45 comprises a top plate 39 somewhat shorter than the bottom plate 36, the top plate also having a downturned flange for attachment by means of the screw 37. The edges of the top plate 37 may be soldered or otherwise secured to the upper 50 edges of the flanges 38. Mounted between the downturned flanges of the two plates 36 and 37 is a third plate 40 having at its upper edge two fingers 41 projecting from the bottom of the socket intermediate the two plates 36 and 39 in 55 position to extend into the openings 24 of the plate casing when the latter is inserted into the socket. When the plate casing is thus inserted the projections 41 engage the inclined surfaces on lugs 42 of the latches to move the latter into 60 unlocking position. Thus the plate is unlocked in response to straight-line or rectilinear relative movement between the casing and unlocking device.

Mounted in a socket 43 in the base 1 is a 65 plunger 44 normally urged outwardly to the position shown in Fig. 2 by means of a spring 45. This plunger has a projection extending into the socket in position to extend through the central opening 23 of the plate casing when the latter is 70 inserted into the socket, thence through the opening 23 into contact with the flange 19 on the end of the plate. The length of the plunger 44 is such that when the plate casing is inserted into the socket the plunger is pressed rearwardly 75 against the action of its spring by contact with

the flange 19 on the plate and, when the plate is unlatched from its casing, the plunger snaps forwardly to the position shown in Fig. 8 thereby partially ejecting the plate from its casing so that the plate may be readily grasped by the fingers for transfer to its printing position 5—6 in 5 Fig. 2. To restore the plate to its casing the latter may be first removed from the socket of the unlocking device and the plate, when slipped back into the casing, is automatically latched 10 within the casing. However, the plate is preferably restored to the casing before the latter is removed from the unlocking device, this being possible for the reason that the latches do not remain in unlatched position but move back to 15 latching position in response to springs 34, the cam action between shoulders 42 and pins 41 simultaneously forcing the casing outwardly of the socket a sufficient distance to permit this 20 automatic restoration of the latches to latching position.

It should be understood that the present disclosure is for the purpose of illustration only and that this invention includes all modifications and equivalents which fall within the scope of 25 the appended claims.

I claim:

1. The combination of a printing plate, a casing therefor, the plate having a compartment shaped to receive the plate snugly, the casing having an 30 opening in one edge through which the plate may be inserted, and a latch in the casing engageable with a shoulder on the plate for latching the plate in the casing, the casing also having an opening in the opposite edge to receive an unlatching device and said latch being movable out of engagement with said shoulder in response to rectilinear movement between said casing and device lengthwise of the casing.

2. The combination of a printing plate, a casing 40 therefor, the plate having a compartment shaped to receive the plate snugly, the casing having an opening in one edge through which the plate may be inserted, and a latch at the opposite edge of the casing for detachably holding the 45 plate in the casing, the casing also having an opening in the opposite edge to receive an unlatching device and said latch being movable out of engagement with said shoulder in response to rectilinear relative movement between said casing 50 and device lengthwise of the casing.

3. The combination of a printing plate having a shoulder at one end, a flat casing having an opening in one edge to receive the plate with said 55 end of the plate foremost, and a latch in the other end of the casing engageable with said shoulder to hold the plate in the casing, the casing also having an opening in the opposite edge to receive an unlatching device and said latch being movable out of engagement with said shoulder in response 60 to rectilinear relative movement between said casing and device lengthwise of the casing.

4. The combination of a printing plate having a flange at one end, a casing shaped to receive the plate with said end foremost, and a latch in 65 the casing engageable with said flange, the casing having an opening to receive an unlocking device and said latch being movable out of engagement with said flange in response to rectilinear relative movement between said casing and device.

5. The combination of a printing plate having a shoulder at one end facing toward the opposite end of the plate, a flat casing having an opening at one end to receive the plate with the shoulder end of the plate foremost, and a latch movable 75

flatwise of the casing into engagement with said shoulder for latching the plate in the casing, the casing also having an opening in the opposite edge to receive an unlatching device and said latch 5 being movable out of engagement with said shoulder in response to rectilinear relative movement between said casing and device lengthwise of the casing.

6. The combination of a printing plate, a casing 10 therefor, the plate having a compartment shaped to receive the plate snugly, the casing having an opening in one edge through which the plate may be inserted, a latch in the casing engageable with a shoulder on the plate for latching the plate in 15 the casing, and an unlatching device having a socket to receive the casing and a projection in the socket for unlatching said plate when the casing is inserted into the socket.

7. The combination of a printing plate having 20 a shoulder at one end, a flat casing having an opening at one end to receive the plate with said end of the plate foremost, a latch in the other end of the casing engageable with said shoulder to hold the plate in the casing, and an unlatching 25 device having a spring-pressed plunger engage-

able with said plate through the other end of the casing to eject the plate from the casing.

8. The combination of a printing plate having shoulders at one end facing toward the opposite end of the plate, a flat casing having an opening 5 at one end to receive the plate with the shoulder end of the plate foremost, latches independently movable flatwise of the casing into engagement with said shoulders for latching the plate in the casing, and an unlatching device having a socket 10 to receive the other end of the casing and means in the socket for simultaneously disengaging the latches from said shoulders and ejecting the plate from the casing.

9. The combination of a printing plate having 15 a latching shoulder, a plate casing having a latch engageable with said shoulder to retain the plate in the casing, a stamping machine shaped to receive said plate for printing purposes, a casing holder on said machine, said holder having a 20 socket to receive said casing, and means in the socket to unlatch and eject the plate for use in said machine while retaining the casing.

STANLEY ANTHONY. 25
